INDIVIDUAL CONDIMENT CONTAINER

David O. Ford, Lynchburg, Va., assignor to The Velporr Corporation, Lynchburg, Va., a corporation of Virginia

Application September 5, 1933, Serial No. 688,250

9 Claims. (Cl. 229—85)

This invention relates to an individual package or container for salt, pepper, or other condiments usually dispensed by means of a shaker.

The object of the invention is to provide a comparatively simple and inexpensive device of this character adapted to contain sufficient condiment for a single service or setting and which may be discarded or destroyed after use.

A further object of the invention is to provide an individual sanitary condiment container constructed of "Cellophane" and in the form of a normally sealed envelope or jacket whereby the contents of the envelope will be effectually protected from moisture and a free flow of the condiment assured when dispensing the same.

A further object is to provide the envelope or container with a plurality of individual pull or rip tabs of different sizes arranged at one end of the envelope and adapted to be selectively manipulated to govern or control the volume of condiment dispensed from the container.

A further object is to so arrange the pull or rip tabs that they gradually decrease in width from one edge of the container to the other so that the user may conveniently select and actuate the particular tab which will permit the discharge of the amount of condiment best suited to his individual use.

A further object of the invention is to provide a sanitary container which may be marketed and distributed by merchants at a relatively small cost and which carries an advertisement that will be preserved so long as the package remains intact.

A still further object of the invention is generally to improve this class of devices so as to increase their utility, durability and efficiency.

In the accompanying drawing, forming a part of this specification, and wherein like numerals of reference indicate corresponding parts in all the figures of the drawing,

Figure 1 is a front elevation, partly in section, of a condiment container constructed in accordance with the present invention.

Figure 2 is a similar view showing one of the pull or rip tabs in elevated position to permit the discharge of the contents of the container.

Figure 3 is an enlarged vertical sectional view taken on the line 3—3 of Figure 1.

Figure 4 is a plan view of the blank from which the container is formed.

Figure 5 is a detail perspective view of one of the upper corners of the container showing the closing flap in elevated position.

The improved condiment holder or container, forming the subject matter of the present invention, is preferably in the form of a flat substantially rectangular envelope or jacket 5 formed of "Cellophane" so that the package will be effectually sealed against the entrance of dampness or moisture and the free flow of the contents.

of the container assured when dispensing the same. The envelope or container is preferably formed from a blank of the construction shown in Figure 4 of the drawing and comprises a back wall or section 6 having integral laterally extending wings 7 adapted to be overlapped and glued or otherwise fastened together at 8 to form the front wall 9 of the container. Depending from the back wall or section 6 is an integral bottom flap 10 which is folded upwardly on the line 11 against and in contact with the front wall 9 and to which it is glued or otherwise permanently secured, as best shown in Figure 2 of the drawing. The upper end of the back wall or section 6 is extended longitudinally to form a top flap 12 adapted to be pressed downwardly on the fold line 13 to form a closure for the discharge end of the container. Depending from the top closure flap 12 are a plurality of separate finger pieces or tabs 14 gradually decreasing in width from one vertical edge of the envelope to the other, the purpose of which is to control the volume or flow of the condiment when dispensing the same. The opposite side edges of the pull or rip tabs 14, at their junction with the closing flap 12, are provided with cuts or incisions 15, and the "Cellophane" is scored or perforated in alignment with said incisions, as indicated at 16, to weaken the tabs and permit them to be readily elevated or detached to expose the contents of the container. The upper end of the front wall 9 preferably terminates short of the fold line 13 and the closing flap 12 is glued or otherwise secured to the upper end of the front wall 9 between the lines 17 and 18.

It will here be noted that the incisions 15 extend partially across the adhesive zone defined by the lines 17 and 18 while the scored or perforated portions 16 of the tabs extend from said incisions up to and intersect the fold line 13. By constructing the tabs in this manner, an initial upward pull on any particular tab will cause it to be readily separated from the adhesive surface between the lines 17 and 18 and a further upward pull on the tab will detach the tab along the line 13 of scores or perforations 16 so as to expose the contents of the container and permit the contents to be readily discharged through the opening 19 formed by the removal or elevation of the adjacent tab. The wings 7, at their junction with the back 6, are preferably formed with vertical corner strips 20, adapted to be folded inwardly, as shown, with their upper ends overlapping and bearing against the closing flap 12, as best shown in Figure 5 of the drawing, so that when the closing flap 12 is folded downwardly and secured to the front wall 9 of the envelope the strips 20 will be folded and thus effectually seal the corners of the envelope or container and prevent accidental escape of the contents thereof.

It will be noted that the lower ends of the rip or pull tabs 14 depend below the lower edge of the closing flap 12 and in convenient position to be grasped by the fingers of the user when it is desired to open the envelope and permit the discharge of the contents thereof. It will furthermore be noted that inasmuch as the pull or rip tabs are independent of each other and gradually decrease in width from one edge of the container to the other, the user may conveniently select the particular tab which will permit the discharge of the amount of condiment best suited to his individual use. For instance, where a relatively large volume of salt or other condiment is desired for immediate use, the large pull tab 14 will be elevated or detached, and where a relatively small volume of condiment is required, as in seasoning vegetables or imparting a saline taste to beer, one of the smaller tabs will be elevated. In this manner, the quantity or flow of the condiment discharged from the container may be regulated according to the requirements of the individual user. Inasmuch as the container is relatively flat, either the front or the rear of the container or both may be used for displaying suitable advertising matter and said advertising matter will be preserved so long as the package remains intact. The "Cellophane" of which the container or envelope is formed renders the same sanitary, and as the envelopes are preferably of a size to be conveniently carried in the pocket and contain only sufficient condiment for a single service or setting, said containers may be destroyed or discarded after having served their purpose.

It will, of course, be understood that the containers or envelopes may be made in different sizes and shapes and any desired advertising indicia may be printed or otherwise impressed on the exterior thereof without departing from the spirit of the invention.

The containers are especially convenient for use at picnic parties, motor parties and for individual use in restaurants and other places.

Having thus described the invention, I claim:

1. A condiment holder including a container having a closure flap provided with a plurality of independent rip tabs extending below the lower edge thereof to form finger-engaging portions and decreasing in width from one edge of the container to the other.

2. A condiment holder including an envelope having its front wall of less height than its rear wall to form a discharge opening, a flap normally closing the discharge opening, and independent rip tabs forming a part of the closure flap and having their lower ends extended below the lower edge of said flap to form finger-engaging portions.

3. A condiment holder including an envelope having a back wall and a front wall spaced from the upper end of the back wall to form a discharge opening, a flap normally closing the discharge opening and secured to the front wall by adhesive material, and a plurality of rip tabs of different widths forming a part of the closure flap and having their lower ends extended below the lower edge of the flap and beyond the adhesive material to form finger-engaging portions.

4. A condiment holder including an envelope having a back wall and a front wall spaced from the upper end of the back wall to form a discharge opening, a flap normally closing the discharge opening and secured to the front wall by adhesive material, and rip tabs forming a

part of the closure flap and having their lower ends extended below the lower edge of the flap and beyond the adhesive material to form finger-engaging portions, there being incisions on opposite sides of the rip tabs and extending partially across the adhesive material.

5. A condiment holder including an envelope having a back wall and a front wall spaced from the upper end of the back wall to form a discharge opening, a flap normally closing the discharge opening and secured to the front wall by adhesive material, and rip tabs forming a part of the closure flap and having their lower ends extended below the lower edge of said flap and beyond the adhesive material to form finger-engaging portions, there being incisions formed on opposite sides of the rip tabs and extending partially across the adhesive material, and perforations disposed in alignment with said incisions and extending therefrom to the upper end of the closure flap.

6. A condiment holder including an envelope having a back wall and a front wall spaced from the upper end of the back wall to form a discharge opening, a flap normally closing said discharge opening and secured to the front wall by adhesive material, the lower edge of the flap being notched to provide independent rip tabs extending below said lower edge and said adhesive material to form finger-engaging portions, there being incisions formed at said notches and extending partially across the adhesive material, and weakened portions formed in the closure flap in alignment with the incisions.

7. A condiment holder including a substantially flat rectangular envelope having a back wall and a front wall spaced from the upper end of the back wall to form a discharge opening, a flap normally closing said discharge opening and having its lower portion secured to the front wall by adhesive material, and a plurality of rip tabs forming a part of the closure flap and extending below the lower edge thereof and beyond the adhesive material to form finger-engaging portions, said tabs gradually decreasing in width from one edge of the envelope to the other.

8. A condiment holder comprising a moisture-proof envelope having a back wall and a front wall, the upper edge of which is spaced from the upper edge of the back wall to form a discharge opening, a flap forming a part of the back wall secured to the upper portion of the front wall by adhesive material and serving to normally close the discharge opening, corner strips forming a part of the front wall bearing against and secured to the closure flap, and a plurality of rip tabs forming a part of the closure flap and having weakened portions extending partially across the adhesive material, said rip tabs gradually decreasing in width from one edge of the envelope to the other.

9. A blank for condiment holders formed from a single strip of material and comprising a central portion having a bottom flap and oppositely disposed side wings, the upper end of the central portion being extended longitudinally to form a closure flap and the end of said flap being notched to form rip tabs decreased in width from one side of the central portion to the other, corner strips forming a part of the wings, there being a fold line extending transversely across the central portion immediately below the rip tabs, and incisions formed on opposite sides of each rip tab.
